UNITED STATES PATENT OFFICE.

GEORGE H. WINTERBOTTOM, OF MANCHESTER, ENGLAND, ASSIGNOR TO
ARCHIBALD WINTERBOTTOM & SONS, OF SAME PLACE.

DESIGN FOR BOOKBINDERS' CLOTH.

SPECIFICATION forming part of Design No. 22,182, dated January 31, 1893.

Application filed June 12, 1890. Serial No. 355,249. Term of patent 14 years.

To all whom it may concern:

Be it known that I, GEORGE HAROLD WINTERBOTTOM, a subject of the Queen of Great Britain, residing at Manchester, England, 5 have invented a new and original Design for Bookbinders' Cloth, of which the following is a specification.

This invention relates to a design for bookbinders' cloth, the surface of which has a grain 10 formed of raised irregular ridges and intermediate depressed portions.

The nature of my design for bookbinders' cloth is clearly shown in the accompanying photograph, to which reference is made.

15 The design on the surface of the cloth is formed of raised irregular ridges *a* and intermediate depressed portions *b*, which impart a characteristic grain to the surface of the

cloth. The ridges or ribs intersect with each other and form with the depressed portions a 20 pattern in the nature of the skeleton fibers of leaves.

Having thus described my design, I claim as new and desire to secure by Letters Patent:—

25 The design for book binders' cloth, substantially as shown and described.

In testimony that I claim the foregoing as my invention I have signed my name in presence of two subscribing witnesses.

G. H. WINTERBOTTOM.

Witnesses:
